SLAB FOUNDATION FOR BUILDINGS OR OTHER STRUCTURES

George Kastner, deceased, late of Milwaukee, Wis.,
by Mascha Kastner, administratrix, Milwaukee,
Wis.

Application December 10, 1938, Serial No. 244,952

4 Claims. (Cl. 72—77)

My invention relates to improvements in slab foundations for buildings or other structures.

The use of a slab foundation in geographic areas, where freezing temperatures cause "heaving" of the supporting earth, has been impractical for even though the interior of the superstructure be heated the margins of the foundation which support the exterior walls are subjected to the movement of frosted earth and are displaced, cracked, and broken by the frost heaved earth or other material upon which the slab is supported.

A solution for the problem has been more urgently required in the period of years since reinforced monolithic slab construction has become popular where moderate temperatures permit of the use thereof, and also where the necessity for deep foundation walls has been eliminated in the new economy of the basementless house. Ways and means have long been sought whereby to permit of the use of a single slab or basementless foundation for a superstructure in the frost affected areas.

Broadly speaking, therefore, it is the object of my invention to provide a slab construction whereby to make it possible in frost affected areas to use a slab foundation upon which a superstructure may be safely and permanently built.

More particularly stated, it is the object of my invention to provide a slab foundation in which the margins thereof, upon which the walls may be supported, are in turn inherently supported by a portion of the slab which has a cantilever construction and in which the real support for said marginal portions of the slab is provided interiorly with respect to said margins and at a point and in a manner which insulates it thermally so that such support will not be affected by the heaving induced by frost.

Another object of my invention is to so construct the margins of a slab foundation as to make them non-responsive to the heaving of frost affected earth or other supporting material.

In furtherance of the above objects it is also the object of my invention to so construct and design the relation between the point of support of the foundation slab and the exterior margin of the slab that this space may be used for the transmission of the heat in the building, by duct or other inclosure, and thus act as an agent in helping to prevent the earth under this foundation support from freezing and heaving.

In the drawing:

Figure 1 shows an end elevation of a house-like superstructure upon a slab foundation, por-

tions of the lower part of the superstructure and of the slab foundation and its earth support being shown in vertical section.

Figure 2 is an enlarged detailed view in vertical section of a foundation, its support, and a fragment of a superstructure wall in position thereon.

Figure 3 is a view similar to Figure 2 and showing the installation of a heating duct in conjunction with a slab foundation.

Figure 4 is a view similar to Figure 3 showing a second form of alternative heating pipe and plumbing installation.

Figure 5 shows in vertical section a marginal portion of a slab foundation in conjunction with a purely frame floor and superstructure embodying one form of the principle of my invention.

Fig. 6 is a plan view of a corner of the frame structure shown in Figure 5.

Like parts are designated by the same reference characters throughout the several views.

In the construction of modern basementless structures, such as low cost dwellings, the conventional shape of building 10 calls for exterior walls 11 which conventionally are supported marginally upon some sort of foundation which, in the northern part of the United States, necessitates a foundation wall extending "below frost". This item alone is a considerable part of the whole cost of an otherwise low cost house. It is for the purpose of obviating the expense of foundation walls that my slab construction is provided.

A slab foundation, or floor 12, embodying my invention, consists of a heavy or reinforced floor for the building comprising the foundation for the superstructure 10 with its walls 11. As shown in Figures 1 to 4, inclusive, the slab is monolithic and is preferably made of concrete either of heavy construction, or reinforced so as to withstand the cantilever action herein described. The earth or soil 13 upon which the slab is supported is substantially leveled according to good engineering practice and provided with a bed of dry material 14 such as cinders or gravel. At some distance from the extreme margins 15 of the slab I provide a downwardly extending foundation fulcrum 16 which, in the light of the principles herein discussed, is positioned sufficiently from the margins 15 and outdoor temperature as to be thermally protected from frost, thus insuring that the fulcrum portion 16 of the foundation is safely rested upon earth 13 which is not to be heaved by frost even in the most severe weather. Externally of the fulcrumed member 16 the slab

12 is unsupported but is of sufficient cantilevered bending strength to support with an adequate factor of safety the weight to be placed marginally thereupon by any walls 11.

- 5 Marginally of the slab 12 I provide an apron 17 which is shaped as clearly shown in the drawing so that a relatively sharp edge is projected downwardly. Against this apron I provide a fill 18 of top soil, or other material, but because of 10 the sharp edge of the lower margin of the apron 17 together with the void space 20 there is no possibility that the heaving by frost of this top soil will lift the slab.

It will be seen from the above description that 15 the portion 19 of the slab which is extended exteriorly of the fulcrumed member 16 is supported on a cantilever principle and externally of the fulcrum 16 a dead air space 20 is provided which is resistent thermally to the loss of heat from 20 the earth supporting the fulcrum. In this space 20 for a superstructure that is to be heated I provide an air space 21 which may be utilized by ducts or pipes for the passage of heated air to the space above the slab 12 or for the return of 25 cooler air from the space above the slab to a warm air heating or ventilating system, and furthermore I may provide in thermally protected relationship to such a duct 21 any other conduits or pipes 22 with which the buildings may 30 be equipped. The passage of relatively warm air through the air space 21 will act to further protect the supporting fulcrum of the slab since heat losses from the ducts will guard against frost adjacent the fulcrum. If the air space 20 is not 35 used as an air passage, the heat from within the building will, of course, assist in holding back the frost line.

In carrying out the principle of my invention in a purely frame dwelling or other building 30, I provide a slab 31 centrally of the building and 40 extending relatively the same distance toward the exterior margin of the building as the fulcrum member 16 is spaced from such margin in the type of construction shown in Figures 1 to 4, inclusive. Exterioly of the slab 31 I provide a 45 floating marginal slab 32 which is in "hinged" relation to the slab 31 and supports no building lead and may move with the heaving of the subsoil. Upon the margin of the slab 31 I provide a sill 33 to be used as the support for ordinary joists 34 which extend outwardly of the slab 31 sufficiently to provide a cantilevered support for the frame exterior wall 35 formed of the usual studding and sheathing 36 and clap-boards 37 or other light weight construction. With this 55 construction the floating slab 32 may move with the frost induced heaving without disturbing the level of the joist 34 since the slab 31 is thermally insulated from the exterior of the building. In this construction space 38 corresponds in its 60 utility to the space 21 in the previously outlined construction. Space 38 (utility space for pipes or ducts) may be confined, by means of enclosing members, to the building perimeter area

between the bottom of joists, top of slab, exterior wall, and the face of the sill. Or it may include the entire space under the building area between the bottom of the flooring (which lays on top of the joists) and the top of the slab. In the first 5 instance an enclosing member would be built up on top of sill 33 to the underside of the flooring. Sill 33 may be continuous, or of individual members placed under each joist.

As shown in Figure 6, the sill 33 terminates at 10 33', and joists 34 supported thereby extend to double header 340, which is spiked or otherwise secured to the joist 34. Joists 341 are spiked to the double header 340 and are supported by the double header, thereby carrying out the structural 15 foundation of the frame building to the extreme corner of the slab foundation but "floated" thereabove so as not to be responsive to any heaving of the outer corner of the foundation.

In areas where severe winters prevail my fulcrum member 16 or the sill 33 will be positioned at a considerable distance from the exterior walls of the building and in more moderate climates or where the heating of the building can be relied upon, the fulcrum or sill member may be more 25 closely adjacent the exterior walls.

I claim:

1. In a slab foundation adapted for support upon frost responsive earth a marginal apron having downwardly converging lower extremities 30 constituting a non-load bearing shield against loss of heat by convection and a fulcrum member for the support of the slab positioned interiorly of the apron and spaced therefrom whereby the fulcrum member may be supported upon thermally protected earth support. 35

2. A monolithic slab foundation having a supporting fulcrum member extending downwardly therefrom and a marginal depending apron for the slab whereby to form an inverted channel 40 exteriorly of said fulcrum member.

3. A slab foundation for a superstructure having exterior walls, an aproned cantilever portion of said slab in position to support said walls, a fulcrum member to support the slab and interiorly spaced with reference to said walls to provide a tunnel-like space between the apron and the fulcrum member and a duct in said tunnel space. 45

4. In a construction of the type disclosed, a slab foundation at ground level, a continuous channel beneath the slab peripherally thereof whereby to provide overhanging margins unsupported by the ground therebeneath, walls and weather protective super-structure supported by the extreme margins of said overhanging portions of the slab in weather protective relation to the entire slab, and an apron depending from the extreme margin of the slab to provide convection current and weather protection for said channel and preserve the ground supported portions of the slab free from frost. 50 55

Deceased.

CERTIFICATE OF CORRECTION.

Patent No. 2,221,193.

November 12, 1940.

GEORGE KASTNER, deceased,
by MASCHA KASTNER, ADMINISTRATRIX.

It is hereby certified that error appears in the printed specification of the above numbered patent requiring correction as follows: Page 2, second column, line 32, claim 1, for the word "connection" read --convection--; and that the said Letters Patent should be read with this correction therein that the same may conform to the record of the case in the Patent Office.

Signed and sealed this 10th day of December, A. D. 1940.
